SNOWSHOE

Frederick T. Paden, Washington, D. C.

Application June 10, 1949, Serial No. 3,169

Term of patent 3½ years

(Cl. D34—14)

To all whom it may concern:

Be it known that I, Frederick T. Paden, a citizen of the United States of America and residing at Collingswood, New Jersey, have invented a new, original, and ornamental Design for a Snowshoe, of which the following is a specification, reference being had to the accompanying drawing, forming a part thereof.

Fig. 1 is a top plan view of the snowshoe omitting the shoe-clamping means;

Fig. 2 is a side elevation of the same, but showing the shoe-clamping means in dotted lines;

Fig. 3 is a bottom plan view of the snowshoe, omitting the shoe-clamping means.

The characteristic features of my design are shown in full lines in said drawing.

I claim:

The ornamental design for a snowshoe, as shown and described.

FREDERICK T. PADEN.
